UNITED STATES PATENT OFFICE.

HYMAN RAUCHBACH, OF NEWARK, NEW JERSEY, ASSIGNOR TO THE RAUCHBACH-GOLDSMITH CO., A CORPORATION OF NEW JERSEY.

LOCKING BAR FOR DRAWER-HOLDING SECTIONS OF WARDROBE TRUNKS.

Application filed April 29, 1925. Serial No. 26,593.

This invention relates, generally, to improvements in wardrobe trunks; and the invention has reference, more particularly, to an improved means for locking the drawers 5 in the drawer section of such a trunk against unauthorized opening.

The invention has for its principal object to provide a simple, strong and easily applied detachable locking bar for the drawer section of wardrobe trunks, by means of which all the drawers of the trunk section are securely locked against opening or removal.

With the various objects of this invention 15 in view the same consists, primarily, in the novel construction of detachable locking bar for the drawer section of wardrobe trunks hereinafter set forth; and the invention consists, furthermore, in the novel arrangements 20 and combinations of the various devices and parts, as well as in the details of the construction of the same, all of which will be more fully described in the following specification, and then finally embodied in the 25 appended claims.

The invention is clearly illustrated in the accompanying drawings, in which:—

Figure 1 is a perspective view of a wardrobe trunk with its hinged body members 30 shown in opened position, and showing the drawer section equipped with the novel locking bar made according to and embodying the principles of this invention; Figure 2 is a fragmentary enlarged face view of the upper end of the locking-bar in operative relation to the upper end of the drawer section of the trunk and Figure 3 is a fragmentary vertical longitudinal central section of the same; Figure 4 is a rear face view of the 40 upper end of the locking bar detached from the trunk; Figure 5 is a detail transverse section, taken on line 5—5 in Figure 4; and Figure 6 is a fragmentary enlarged face view of the lower end of the locking bar 45 in operative relation to the lower end of the drawer section of the trunk.

Similar characters of reference are employed in all of the hereinabove described views, to indicate corresponding parts.

Referring now to said drawings, the reference character 7 indicates the garment holding section of a wardrobe trunk, and 8 the drawer holding section in which are slidably disposed a plurality of drawers 9, providing 50 a vertical tier thereof, mounted to withdraw

outwardly from the inner open side or face of said section 8. Said trunk sections are hinged together along adjacent vertical sides so as to close one upon the other in the manner common to such trunks. 60

The novel means for locking said drawers 9 into the interior of the trunk section 8, to hold the same both against accidental displacement and against unauthorized opening, consists in a vertically disposed detachable locking bar, with means to affix the same to the trunk section in extension across the outer faces of the several drawers 9. 65

Said locking bar comprises a, preferably metallic, main bar-member 10. Connected in longitudinal slideable relation to the upper end of said main bar-member 10 is an adjustable extension member 11, having at its opposite sides longitudinal guide-flanges 12, which extend around or embrace the longitudinal marginal portions of said main bar-member 10. The rear side of said extension member 11 is provided in connection with one or both of said guide flanges 12 thereof, with longitudinally spaced laterally projecting stop lugs 13, and the upper extremity of said main bar-member 10 is provided with a rearwardly projecting abutment lug 14, which extends into the path of movement of said stop lugs 13 and intermediate the latter, so that engagement of said abutment lug 14 by one or the other of said stop lugs 13 will serve to limit the sliding movement of said extension member 11 in each direction. 70 75 80 85 90

Suitably affixed to the lower end portion of the drawer holding section 8 of the trunk is an anchor plate 15. Said anchor plate 15 is disposed in horizontal plane, and is provided with an outwardly projecting free end portion having a keeper slot 16 of a length less than the width of the lower end of said main bar-member 10. Said main bar-member 10 is provided, adjacent to its lower end with an indented notch 17, which enters laterally from one longitudinal edge of said bar-member 10, to reduce the width of the latter to correspond substantially to the length of said keeper slot 16. The lower extremity of said bar-member 10, below the 105 position of said notch 17 is rounded at the corners, as indicated at 18 in Figure 6 of the drawings. When the bar-member 10 is in operative coupled engagement with said anchor plate 15, the lower end of the former 110

is passed or extended through the keeper slot 16 of the latter, the notch 17 of the bar-member 10 straddling one marginal side portion of the anchor plate beyond one end 5 of said keeper slot 16. When thus arranged and engaged with said anchor plate, the bar-member 10 cannot be either accidentally or intentionally vertically displaced from operative attached relation to trunk section 10, except by freeing the upper end of the bar-member 10, and thereupon transversely swinging the bar-member to the right, to thereby turn its lower end out of operative engaged or coupled relation to the anchor plate, in the manner indicated by the dotted representations of the bar-member shown in 15 said Figure 6 of the drawings.

Suitably affixed to the upper end portion 20 of the drawer holding section 8 of the trunk, and in vertical alignment with the aforesaid anchor plate 15, is a means with which the upper end of the extension member 11, which is connected with said bar-member 10, may be interlocked. This means comprises a keeper lug 19, the rear end portion 20 of which is secured by suitable means to the body of the trunk end. Said keeper lug 19 is preferably downwardly off-set from the plane of the under side of the trunk end 25 wall, and is disposed to project outwardly beyond the outer face plane of the drawers 9, when the latter are in closed position. Secured in aligned relation to or with the rear end portion 20 of said keeper lug 19 is the 30 rear end portion 21 of a striker plate 22. Said striker plate 22 is downwardly spaced from the keeper lug 19, and is provided in its free end portion with a latch receiving slot or socket 23. As shown in the drawings, the front wall of the upper drawer of 35 the tier of drawers 9 is provided with an opening 24 through which said keeper lug 19 and striker plate 22 may project, when said drawer is closed, so as to be disposed beyond the face plane of said drawer.

The slideable extension member 11 of the drawer locking bar is provided, at its upper extremity, with an inwardly turned portion or lip 25. Secured to the inner side of said 40 extension member 11 is a locking mechanism 26 having a key barrel 27 projecting through the body of said extension member 11 so as to be accessible at the front face of the latter. Said locking mechanism 26 includes an upwardly projecting beveled spring bolt or latch 28. Also secured to said extension member 11, so as to project from its outer face, is a knob or finger piece 29, by means of which said extension member may be 45 manipulated.

When the drawers 9 are closed into the trunk section 8, and it is desired to apply the locking bar for the purpose of locking the drawers against displacement or removal, the lower end of the bar-member 10

is coupled with the anchor plate 15, in the manner already above indicated, and the bar-member 10 is swung into perpendicular position. The slideable extension member 11, when the bar-member 10 is detached, occupies a downwardly slid or lowered position on the upper end of the latter. When, therefore, in applying the bar, the bar-member 10 is brought to the aforesaid perpendicular position, the knob or finger-piece 29 is 75 grasped by the operator, and an upward sliding movement is imparted to said extension-member, whereby the same is lifted until the lip 25 thereof abuts or is stopped against the keeper lug 19, thus bringing the 80 beveled face of the spring bolt or latch 28 opposite the end of the striker plate 22. Such positioning of the parts having been attained, the operator thereupon presses inwardly against the face of the extension member, thereby springing the bolt or latch 28 beneath the striker plate 22 until the same is registered with and upwardly sprung into the latch receiving slot or socket 23, thus completing the operative locked engagement of the upper end of the locking bar with the trunk section. Intermediate the upper and lower ends of the trunk section 8 there may be provided a hook-like retaining lug 30, beneath which the bar-member 10 is engaged when the same is 85 swung to operative perpendicular position. This retaining lug 30 may be suitably secured to a stationary part of the trunk section, as, e. g., an intermediate drawer slide 90 or rest. The retaining lug 30 serves to prevent outward forcing, by bending, of the bar-member 10 when the locking bar is in operative locked position. To remove the locking bar to release the drawers 9, a 95 proper key must be inserted in the key-barrel 27 and manipulated to retract the spring bolt or latch 28, whereupon the upper end of the locking bar may be released, and by reversing the above described operations 100 entirely detached from the trunk section 8.

From the above description, it will be quite apparent that this invention provides a very strong and easily manipulated locking bar for the drawer holding section of 105 wardrobe trunks, provided with a novel and simple means for interlocking the same in operative position, and thus securely held against unauthorized removal, except by the application thereto of a proper key.

I am aware that some changes may be made in the various devices and parts, as well as in the details of the construction of the same, without departing from the scope of this invention as described in the foregoing specification, and as defined in the appended claims. Hence, I do not limit this invention to the exact arrangements and combinations of the devices and parts as set forth in the foregoing specification, nor do 115 120 125 130

I confine myself to the exact details of the construction of said parts as illustrated in the accompanying drawings.

I claim:—

5 1. In a wardrobe trunk, one member of which constitutes a drawer holding section provided with removable drawers, a detachable locking bar for extension across the outer faces of said drawers, a fixed anchor 10 plate connected with the lower end wall of said trunk section, said anchor plate having a transverse slot of a width less than the width of said locking bar, said locking bar having a laterally indented notch in one side 15 thereof adjacent to its lower extremity whereby said extremity may be hooked through the slot of said anchor plate and thus be anchored against displacement when said locking bar is swung to operative vertical 20 position across said drawers, an extensible member slidably connected with the upper free end of said locking bar, a key-controlled spring latch mechanism carried at the upper free end of said extensible member, and means in fixed connection with the upper end wall of said trunk section with 25 which said latch mechanism may be interlocked, said latter means comprising an outwardly projecting striker plate having a 30 socket to receive said spring latch, and a keeper plate spaced above and overhanging said striker plate with which the upper extremity of said extensible member may be brought into stopped engagement to properly 35 position said spring latch relative to said striker plate.

2. In a wardrobe trunk, one member of which constitutes a drawer holding section provided with removable drawers, a locking bar to extend across the outer faces of said drawers, means for detachably coupling the lower end of said bar with the lower wall of said trunk section, an extensible member telescopically slidable on the upper end of 40 said bar, an outwardly projecting striker plate fixed to the upper wall of said trunk sections having its free end portion downwardly off-set from the plane of said upper wall, said free end portion having a socket, 45 a key-controlled spring latch mechanism carried on the upper end portion of said ex-

tensible member whereby in operation said latch mechanism may spring upwardly into said striker plate socket to retain said locking bar against outward displacement, and 55 a transverse rearwardly projecting lip at the upper extremity of said extensible member adapted in operation to engage over the upper surface of said striker-plate to hold said extensible member and its latch mechanism against downward displacement from 60 operative locked position.

3. In a wardrobe trunk, one member of which constitutes a drawer holding section provided with removable drawers, a locking bar to extend across the outer faces of said drawers, means for detachably coupling the lower end of said bar with the lower wall of said trunk section, an extensible member telescopically slidable on the upper end of 70 said bar, an outwardly projecting striker plate fixed to the upper wall of said trunk section having its free end portion downwardly off-set from the plane of said upper wall, said free end portion having a socket, 75 a key-controlled spring latch mechanism carried on the upper end portion of said extensible member whereby in operation said latch mechanism may spring upwardly into said striker plate socket to retain said locking bar against outward displacement, and a transverse rearward projecting lip at the upper extremity of said extensible member 80 adapted in operation to engage over the upper surface of said striker-plate to hold said extensible member and its latch mechanism against downward displacement from 85 operative locked position.

In testimony that I claim the invention set forth above I have hereunto set my hand this 14th day of February, 1925.

HYMAN RAUCHBACH.
